UNITED STATES PATENT OFFICE.

MICHAEL A. KENNEDY, OF BOSTON, MASSACHUSETTS.

RUBBER FABRIC FOR HEELS OR THE LIKE.

SPECIFICATION forming part of Letters Patent No. 723,876, dated March 31, 1903.

Application filed November 30, 1900. Serial No. 38,085. (No model.)

To all whom it may concern:

Be it known that I, MICHAEL A. KENNEDY, a British subject, and a resident of Boston, county of Suffolk, Massachusetts, have invented certain new and useful Improvements in Rubber Fabrics for Heels or the Like, of which the following is a specification.

My invention comprises certain improvements in rubber fabrics by which I am able to produce a fabric of this class having highly elastic and resilient properties in which is secured the greatest attainable degree of compressibility without materially sacrificing the permanence or durability of the fabric. The form of this fabric herein shown is especially suitable for cushion heels and soles for shoes and is also valuable for other purposes in which the properties which it possesses are desirable.

Generally speaking, the fabric consists of a piece of vulcanized rubber comprising a relatively firm or solid exterior face combined with a relatively yielding and elastic interior portion. A marked feature of this interior portion consists in a construction characterized by a series of passages or cells so arranged on either side of an intervening or intermediate elastic web or wall that the compression of the fabric distends or stretches the web, so that the original form of the fabric is restored by the retractile or elastic properties of stretched rubber.

Another improved feature of the invention consists in forming the fabric with a relatively yielding interior or center portion and a relatively firm or solid wearing face, said wearing-face having embedded within itself strips of textile fabric set edgewise to the wearing-surface.

In the accompanying drawings I have illustrated but a single form of my improved fabric, and it will be understood that variations in the particular construction and arrangement may be made without departing from the spirit of my invention.

Figure 1 is a bottom plan view of a rubber heel for shoes embodying the principles of my invention. Fig. 2 is a sectional plan view viewed from the bottom, the plane of said view being indicated by broken line 22 in Fig. 3. Fig. 3 is a central transverse section. Fig. 4 is a central longitudinal section of the

heel. Fig. 5 is a plan view partly broken away to show the peculiar cellular construction of the fabric. Fig. 6 is a perspective view looking down upon the top of the fabric, the cells in this instance being made rectangular instead of round in order to more clearly mark the distinctions between the continuous walls or webs and their short intermediate webs.

In its main features the heel comprises a relatively firm or solid bottom wall *a*, side walls *b*, and a central portion *c*, so constructed as to possess a relatively high degree of compressibility, so as to be much more yielding and elastic than the walls *a* and *b*. Considered in its broadest aspects, I may employ any suitable construction that gives a relatively high degree of yield or compressibility so long as I provide a heel with relatively firm exterior walls combined with a relatively yielding interior. In the preferred form of my invention, however, I so construct this interior portion that its compression results in distending or stretching the rubber, and its expansion or restoration to its normal state is effected by the tension or retractile force of the stretched rubber, as will be hereinafter explained, and this is a very marked feature of my invention, for if a good quality of rubber be used the fabric instead of becoming broken down and permanently compressed will retain its original elasticity so long as the rubber itself retains its elastic properties. The yielding center portion *c*, as herein shown, comprises a series of oblique passages or cells *c'*, separated by comparatively thin elastic webs or walls *c*², which, as shown, are also inclined at an angle to the bottom face or wall of the fabric.

By referring to Figs. 5 and 6 it will be noticed that the passages or cells *c'* are arranged so as to form straight rows across the heel, so that the cells of each row or series are staggered with reference to the cells of the series immediately in front or immediately behind it. The effect of this arrangement is to form a series of continuous webs or walls *c*² running crosswise of the heel and which in this instance are shown as oblique or inclined to the top and bottom of the heel, which continuous webs serve to separate the cells of the two adjacent series. These con-

tinuous webs are connected with each other by short connecting-webs c^3 , which form the dividing-walls between the individual cells in each series. It will also be noticed that 5 the connecting-webs c^3 are offset with reference to each other, so that each web c^3 is in alignment with the cells c' in the two adjacent series or rows. In consequence of this arrangement when the fabric is pressed upon 10 these short connecting-webs c^3 sink into the oblique cells immediately behind them, which the webs c^3 partly overhang. The compression of the fabric therefore results in stretching both the continuous web c^2 and the connecting-webs c^3 . When the pressure is removed, the tension of the stretched rubber tends to pull the webs back into their normal 15 position. This action will continue so long as the elasticity or stretch of the rubber endures, 20 and as in good qualities of rubber this will last for a very considerable time the fabric will retain its elasticity for a long period, and thus the tendency to break down and remain permanently compressed is overcome. The 25 particular form and arrangement of the cells and webs may be modified or changed without losing this property, so long as the fabric is characterized by a continuous web separating two series of cells having a relatively 30 staggered arrangement, so that the cells of one series are in alignment with the dividing walls or webs which separate the individual cells of the next series.

For convenience in distinguishing I may 35 call the webs c^2 , which divide one whole series of cells from the next, the "continuous" webs, and may designate the short webs c^3 , which form the dividing-walls separating the individual cells in the same series, as the "connecting-webs," since they also serve to connect the two adjacent webs.

In order to prevent the rapid wearing off of 40 the bottom of the heel, I may embed therein strips of canvas or textile material to form a more durable wearing-surface. This canvas 45 may be embedded in the rubber in any suitable manner; but I have herein shown an arrangement comprising a series of parallel canvas strips a' set edgewise to the bottom of 50 the heel. It will be noticed, too, that this canvas insertion is set in a little distance from the outer edge of the heel, so that the outer edge may be given the surface finish, which could not be done as effectively if the canvas 55 projected to this outer surface. While I prefer the arrangement of canvas herein shown, it will be understood that I do not confine myself to such an arrangement as that actually described.

60 As the heel will usually be fastened by means of nails or the like, I may form the bottom portion with a series of nail-holes a^2 , and in order to provide a firm seat for the heads of the nails I may employ a perforated stiffening-plate d , which is embedded in the heel 65 at a considerable distance from the bottom surface, so that the heads of the fastening-

nails may lie well within the wearing-surface of the heel.

It will be noticed that the compression of 70 the heel causes the plate d to play slightly up and down on the nails which are driven into the heel-seat of the shoe.

The top of the heel or fabric may be closed 75 with a layer of textile fabric or other suitable material e , which may be cemented or otherwise secured to the top of the heel. This layer e serves to prevent undue spreading of the yielding or compressible portion of the heel and may at the same time serve to confine air within the cells c' , so that the natural 80 elasticity of the rubber is reinforced by the action of the confined air when the heel is compressed. This pneumatic cushioning of the heel is a valuable feature and it will be 85 noticed that the cells are independent of each other, so that if one or more of them be punctured the remaining cells are not affected thereby.

While I have shown and described this fabric as made in the form of a heel for a shoe, it is of course obvious that it may be applied 90 to many uses other than that described in which a considerable degree of resilience is desired.

Without attempting to set forth the various 95 modifications in form and construction that may be made in the practice of my invention or all the uses to which said invention is applicable, what I claim is—

1. A resilient fabric for heels or the like 100 consisting of a strip of vulcanized rubber comprising a relatively firm outer face and an interior yielding portion characterized by one or more thin elastic webs forming a dividing 105 wall between two series of cells or perforations so arranged that the compression of the fabric stretches the web bodily whereby the fabric is restored to its original form by the retractile force of the stretched web substantially as described.

2. A resilient fabric for heels comprising a 110 piece of vulcanized rubber formed with a relatively firm exterior face and with a relatively yielding and elastic interior portion containing a series of inclined webs separated by oblique passages or cells substantially as described.

3. A resilient fabric for heels or the like 120 comprising a relatively yielding and elastic center portion and a relatively firm or solid wearing-face said wearing-face having embedded therein a strip of textile fabric set edgewise to the wear-surface substantially as described.

4. A resilient fabric for heels or the like 130 comprising a relatively yielding and elastic center portion and a relatively firm or solid wearing-face, said wearing-face having a piece of textile fabric embedded therein substantially as described.

5. A resilient fabric for a heel comprising a yielding interior portion and a relatively firm or solid face, said face having textile fab-

ric embedded therein at some distance from the edge of the heel, substantially as described.

6. A resilient fabric for a heel comprising a yielding portion and a relatively firm or solid face, and a perforated plate embedded in the solid face some distance below the surface of that face to provide a seat for the fastening-nails substantially as described.

10 7. A resilient fabric comprising a relatively firm or solid layer of vulcanized rubber and another layer containing series of cells or passages separated by an intermediate web, the cells on one side of the intermediate web being offset or staggered with reference to the cells on the other side of said web substantially as described.

15 8. An elastic collapsible fabric characterized by a series of oblique elastic webs extending in one direction of the fabric and a

series of elastic webs arranged to connect the oblique webs at intervals, the respective webs of each series being separated by oblique cells formed between them.

20 9. An elastic collapsible fabric containing a series of oblique webs extending in one direction of the fabric and separated from each other by a series of cells, short transverse elastic webs arranged to separate the individual cells of each series and to connect the oblique webs, the cells on one side of the oblique web being in line with the connecting-webs on the other side of said web, substantially as described.

25 In witness whereof I have hereunto set my hand this 26th day of November, 1900.

M. A. KENNEDY.
